CLAIM

[21] Appl. No.: 578,867

The ornamental design for a hook for attaching the net to the frame of a portable goal, as shown and described.

[22] Filed: Sep. 6, 1990

DESCRIPTION

[52] U.S. Cl. D8/367

FIG. 1 is a perspective view of a hook for attaching the net to the frame of a portable goal showing my new design, the broken line showing a hooked net is for environmental illustration only and forms no part of the claimed design;

[58] Field of Search ..... D8/367, 398, 389, 396, D8/385, 370, 356, 354, 383; 24/115 K, 265 D, 300; D21/258, 48; D12/317; 248/500

FIG. 2 is a top plan view of the hook for attaching the net of the frame of a portable goal in FIG. 1 (omitting the net);
